CLAIM

The ornamental design for a case for a scorekeeping device, as shown and described.

DESCRIPTION

FIG. 1 is a top plan view of a case for a scorekeeping device showing my new design;

FIG. 2 is a left side elevational view thereof; the right side elevational view being identical;

FIG. 3 is a front elevational view thereof; the rear elevational view being identical; and,

FIG. 4 is a bottom plan view thereof.

The broken line showing of a band is for illustrative purpose only and forms no part of the claim.

FIG. 1

FIG. 2

FIG. 3

FIG. 4
